(57) **CLAIM**

The ornamental design for top for beverage container, as shown.

DESCRIPTION

FIG. 1 is an isometric view of the top for beverage container showing my design;

FIG. 2 is an orthographic top view of the top for beverage container;

FIG. 3 is an orthographic side view thereof, all side views being the same; and,

FIG. 4 is an orthographic bottom view thereof. The broken lines show part of the structure that forms no part of the claim.
